United States Patent Office.

WILLIAM S. McNEIL, OF SPRINGFIELD, MASSACHUSETTS.

Letters Patent No. 82,017, dated September 8, 1868.

IMPROVEMENT IN HAMMER AND MALLET.

The Schedule referred to in these Letters Patent and making part of the same.

TO ALL WHOM IT MAY CONCERN:

Be it known that I, WILLIAM S. McNEIL, of Springfield, Hampden county, Commonwealth of Massachusetts, have invented a new and useful Improved Tinner's Hammer; and I do hereby declare that the following is a full and exact description thereof, reference being had to the accompanying drawings, and to the letters of reference marked thereon.

In the drawing—

Figure 1 is a side view of my hammer,

Figure 2 a section view of a part, and

Figures 3 and 4 detail views of the parts.

This invention consists in arranging a combination of hammer and mallet for tinner's use, so that the mallet may be removed, when not used, and readily replaced when desired.

In construction, I form my device of a cylindrical piece, A, into which the handle, K, is placed, having a hammer-head, C, on one side, and a socket, a, upon the other. Into this socket the mallet, B, fits, it being formed with a tenon, b, and shoulder, so as to make a firm and neat joint.

This mallet may be fastened in with a screw, or other convenient means, if necessary.

Upon the face of the hammer-head C, in front, is formed a pene, c, for various purposes required in tin-work.

This hammer is peculiarly useful in the roofing of houses, where it is inconvenient to carry two separate tools, such being necessary in the operations.

In Figure 5 is shown a diagram of another method of arranging these parts.

In this, the handle K is set into a wooden mallet-head, L, the hammer-head, m, of metal, being screwed into the head L, as shown by the dotted line. This is for the purpose of rendering the combination-tool lighter than is obtained by the former method.

By arranging the pene c upon the hammer-head C, instead of the opposite end, now occupied by the mallet, I am able to use the pene without turning the hammer, as is necessary with hammers as commonly arranged.

Now, having described my invention, what I claim as new, and desire to secure by Letters Patent, is—

1. A hammer and mallet combined, in which the mallet B fits in a socket, a, constructed in the piece A, having the head C with pene c, the parts being combined and arranged substantially as herein shown.
2. The arrangement of the pene c upon the head, C, of the hammer, substantially as shown.

WM. S. McNEIL.
